Application February 12, 1947, Serial No. 728,107

17 Claims. (Cl. 201—48)

1

This invention relates to adjustable electric heating devices, especially devices such as heating pads and the like, having controls providing for a plurality of heat adjustments in such devices.

The invention is concerned with improvements in the devices of my Patent Number 2,415,858 entitled "Switch device" and copending patent application Serial Number 721,979, filed January 14, 1947, entitled "Rheostat".

An object of the invention is to provide in a heating pad an improved small and compact resistor-type control device the casing or housing of which has a cooler operating temperature than was heretofore obtained, thereby eliminating the necessity for separate heat-insulating plates on the casing exterior, or similar insulating instrumentalities previously required.

In small, compact resistor-type control devices of the type referred to, a resistor element is located within the casing of the device, which casing is formed of molded insulating material. The resistor, for reasons of economy of space and convenience of mounting and assembly, is press-fitted and carried in a recess molded in the inner surface of the exterior wall of the casing. In the past, the recess was made to closely fit and conform to the resistor element and during the normal operation of the device, the element became quite hot and imparted its heat to the casing wall, in addition to other ways, by direct contact therewith. The heat exchange between the resistor element and the casing wall was quite efficient, and as a result the wall of the casing became hot to the touch, and a user if he noticed this would be likely to think that the control device was operating improperly, or that a dangerous condition was developing.

To offset the effect of this, in the past, a heat-insulating plate was provided to cover the portion of the casing which evidenced the most heat, the plate being made as ornamental as possible under the circumstances. While this in general proved to be satisfactory in reducing the heat which a user felt, it represented an added expense and detracted to an extent from the appearance of the control device.

According to the present invention an improved mounting is provided for the resistor element of the control device, which results in a much less efficient heat exchange between said element and the wall of the casing, thereby resulting in the casing having a cooler operating temperature and doing away with the need for an exterior heat-insulating plate. In accomplishing this, the re-

2

sistor element is so mounted that an appreciable air space exists between it and the interior surface of the casing wall, the said space eliminating heat exchange through direct conduction and reducing considerably heat exchange by radiation. I have found that by providing a space in the neighborhood of $\frac{1}{16}$ " or so, the heat exchange is so reduced that the exterior of the casing is not unduly warm to the touch and therefore it is not necessary to employ any auxiliary heat-insulating device, such as the external heat-insulating plate mentioned above.

Another object of the invention is to provide an improved contact organization, in a small and compact control device of the above type, which eliminates the possibility, heretofore present, of the resistor element of the device being inadvertently connected in the circuit to carry the whole current thereof and therefore become overheated, should the proportions of the component parts of the device vary slightly due to departure from manufacturing tolerances, etc.

In the control devices of my patent and application above referred to, the circuit control was effected by a pair of electrically connected switch blades extending in opposite directions and respectively engaging, on the one hand a metal contact segment, and on the other hand the resistor element of the device. It was intended that the switch blades engage the contact segment and the resistor element substantially simultaneously when actuating the device from "off" to "low" position, or that the contact segment be engaged slightly ahead of the resistor element. However, due to manufacturing variations in the dimensions of the various cooperable parts, it sometimes happened that the resistor element was engaged prior to engagement of the contact segment, and the control device left in this condition. As a result, the resistor element carried the entire current through the device, which it was not designed for, and therefore became unduly overheated. In these prior control devices the contact between the switch blades and the resistor element was established through a metal retainer finger which was located to overlie one end of the element and hold the latter in position in the casing of the device.

According to the present invention the above difficulty is overcome without increasing the size of the control device or adversely affecting the range of heats of the pad by a novel organization wherein the metal retainer finger is insulated from the resistor element so that even if the finger should be contacted first, before contact is estab-

lished to the metal contact segment, no current will flow solely through the resistor element and therefore the latter will not become overheated. In addition to eliminating the possibility of overheating of the resistor element, the insulating of the retainer finger results in a new, very low heat setting for the heating pad, and in effect extends the range of adjustment thereof.

As the contact blades of the improved control device are advanced from "off" to the starting low position, contact is positively established between one blade and the contact segment before the other blade leaves a retainer finger for the resistor element, and therefore there is positive assurance that at no time will the resistor element be made to carry the entire current through the control device.

For the starting low position of the switch blades, due to current being conducted from the latter solely through the contact segment because of the insulation of the retainer finger for the resistance element, the entire current through the control device will be caused to flow through the thermostat heater in the heating pad, and this will cause a high rate of activity of the thermostat and a consequent very low temperature in the pad, which very low temperature I term a "low-low" heat.

Another object of the invention is to provide an improved contactor assembly which is arranged for quick and economical assembling of the component parts, and is so constructed that when once assembled the parts constitute a unit and are not separable from each other to cause difficulty when mounting the assembly in the casing of the control device.

In the devices of my above-referred-to patent and application, the contact assembly comprised a rotatable member having a spindle and a manually engageable actuating wheel, and comprised oppositely extended switch blades associated with the wheel and spring urged therefrom by a helical compression spring. In this assembly the switch blades were not permanently fastened to the actuating wheel and at times difficulty was experienced in holding the switch blades and spring to the wheel while the assembly was installed in the casing of the device.

According to the present invention this difficulty is overcome by the provision of an improved switch blade structure wherein hooked deformable arms are provided for cooperation with shoulders on the actuating wheel of the assembly, the arms being so arranged that when the switch blades and actuating wheel are brought together under pressure the arms will be deformed and hook themselves over the shoulders of the wheel thereby to permanently retain the switch blades on the wheel. As a result, the contactor assembly remains as a unit, the component parts of the assembly being permanently secured in place. This improved assembly may be installed in the casing of the control device quickly and without difficulty, thereby reducing the assembly costs of the device.

Other features and advantages will hereinafter appear.

In the accompanying drawings:

Figure 1 is a plain view of a control device made in accordance with the invention.

Fig. 2 is a similar view of the control device, but with the cover removed.

Fig. 3 is an axial section of the control device taken on the line 3-3 of Fig. 1.

Fig. 4 is a transverse section of the device taken

on the line 4-4 of Fig. 2, but with the cover in place.

Fig. 5 is an exploded view of the contactor assembly of the control device, illustrating the method of assembly of the component parts, and the tools used in such assembly.

Fig. 6 is a view like Fig. 5, but with the parts of the assembly brought together just prior to their being permanently joined.

Fig. 7 is an end view of the assembled contactor assembly.

Fig. 8 is a perspective view of the contactor of the assembly prior to attachment to the actuating wheel, and

Fig. 9 is a schematic diagram of the control device and a heating pad controlled thereby.

The control device of the present invention as shown includes a casing 20 which may be conveniently manufactured of molded plastic. The casing 20 when assembled is of elongate shape having tapered ends and a substantially oblong central transverse cross-section. It is separable into two parts 20a and 20b along a substantially axial plane parallel to its broader lateral surface.

The two parts are held together by means of screws 21 adjacent opposite ends of the casing, and at each end the edges of the casing parts are recessed to provide apertures 22 and 23 (when the two halves are assembled) to receive conductors extending into the interior of the control device.

Approximately at the center of the two casing halves 20a and 20b, their opposite lateral edges are recessed to form a pair of longitudinal slots 24 when the casing is assembled, through which an adjustment disk 25 carried within the casing may extend. The casing portion 20b is also provided with a sight opening or aperture 26 for observing a visual indicator or dial 27a. The sight opening 26 preferably has a central arrow tip 26a at one side thereof for cooperation with the dial 27a to provide a reference point thereof.

A pair of conductors 28 entering the casing 20 through the aperture 22 thereof is adapted to connect the control device with a source of electric power. The ends of these conductors extend through grooves 29 in the interior of the casing on opposite sides thereof and are connected to a pair of terminal screws 30 and 31 carried by a web 32 formed in the casing half 20a. A web 33 is also formed in the central wall of the casing half 20a and comprises a semi-circular portion 33a adjacent the web 32 and an oblong portion 33b extending toward the opposite end of the casing. The breadth of the oblong portions 33b of the web 33 is such as to allow for a pair of clearance grooves 34 and 35 which extend between the said portions and the lateral casing walls to receive connectors by-passing the said web.

A central recess 36 substantially at the center of the casing half 20a is formed in the web 33 with an annular bearing surface 37 surrounding a central spindle-receiving cavity or bearing 38 at its base. The opposite half 20b of the casing is provided with a similar bearing cavity 39 disposed directly opposite cavity 38, said cavities receiving the ends of a spindle 40 serving as the shaft for the indicator dial 27a and the adjustment disk 25. The translucent dial 27a is attached to a collar 41 on the upper end of the spindle 40 adjacent the bearing 38, and a portion of its surface extends under the sight opening 26 which is offset from the axis of the spindle.

The adjustment disk 25 may be formed for in-

stance of molded plastic material and is of generally circular shape. It comprises a hub 42 molded on spindle 40 on the opposite side of the disk from collar 41, its lower surface forming an abutment to engage the bearing surface 37. The peripheral edges of the disk 25 extend through the lateral slots 24, so that the protruding arcuate portions of the said disk are available for its manipulation.

The portion 33b of web 33 has a transverse slot 45 therein, adjacent the circular recess 36, for receiving connector or resistor means, and beyond the slot two screws 46 and 48 are threaded into the web. An elevated portion of the web 33 beyond slot 45 forms an additional web 49, which carries a pair of terminal screws 50 and 51 adjacent end aperture 23. As indicated in Fig. 2, the three conductors 52a, 52b and 52c are connected to terminal screws 50, 51 and 48, respectively. These conductors are adapted to connect the control device to a device such as a heating pad to be controlled.

Terminal 30 is connected directly to terminal 51 by means of an insulated conductor 53 which lies in lateral groove 35 of the casing part 20a. Terminal 51 carries a resilient conductor strip or spring contact 54 which extends through lateral groove 34 of casing part 20a to a point opposite the spindle 40 or its bearing 38. An angular tip 55 on the spring contact 54 extends inward into the circular recess 36 through a radial groove or slot 56 in the side of the web 33, terminating just short of the hub 42. The spring contact 54 is mounted so that its resilience normally urges its tip 55 toward the top of the slot 56 in web 33.

A metal contactor 57, Fig. 8, comprises a circular cup-shaped portion 57a having a central aperture in its base adapted to receive the hub 42 of spindle 40, and comprises a pair of diametrically opposite radial blades or wings 57b, each having a pair of folded lateral flanges or arms 57c. The exposed surface of each of the wings 57b is convex. The arms 57c are adapted to engage the edges of a pair of correspondingly disposed apertures 58 in the adjusting disk 25 so that the disk 25 and contactor 57, when assembled as illustrated in Figs. 3, 6 and 7, are coupled for mutual rotation.

A coiled compression spring 59 surrounds hub 42 and is supported at one end against the face of the disk 25. The opposite end of the spring 59 bears upon the base of the cup-shaped portion 57a of contactor 57. Thus, when the control device is assembled, spring 59 urges the contactor 57 toward the wall of the casing half 20a, and presses wings 57b toward the upper surface of web 33, Fig. 3, while the arms 57c thereof engage the apertures 58 in the disk so that the contactor is rotatable thereby.

According to the present invention the contactor 57 is so arranged that it may be easily and quickly permanently assembled to the adjustment disk 25 so that these may be handled as a unit, thereby facilitating their assembly into the casing 20, and facilitating the assembly of the entire control device. In accomplishing this the arms 57c of the contactor 57 terminate in hooks 57d which extend inwardly in pairs, toward each other, and the webs 57c, as may be clearly seen in Figs. 5 and 6, extend at an angle with respect to the end surface of the cup-shaped portion 57a. The arrangement is such, referring to Figs. 5 and 6, that the hooked arms 57c may be extended through the openings 58 in the adjustment disk

25 by bringing the disk and the contactor 57 axially together. Prior to such movement, of course, the spring 59 is interposed so as to be positioned on the hub 42 of the disk. After bringing together the contactor 57 and adjustment disk 25, further pressure on the wings 57b will cause these to become straightened and aligned with each other, and in so doing the hooked arms 57c will be swung inwardly toward each other causing the hooks 57d thereof to overlie the shoulder or end of the hub 42 of the disk for engagement therewith. It will be seen that upon this deforming pressure being removed, the expansion of the coil spring 59d will cause the hooks 57d to be held in engagement with the hub 42 of the adjustment disk. Thus the contactor 57 is now permanently attached to the disk and cannot inadvertently be separated therefrom.

Preferably the contactor 57 is assembled to the adjustment disk 25 by the use of tools 25a and 57e, as shown in Figs. 5 and 6, these tools being adaptable for use in a light punch press such as a foot or kick press, and enabling the operation of assembling the contactor to the disk to be quickly and economically carried out. Such assembly is preferably done prior to assembly of the translucent dial 27a to the spindle 40.

The tip 55 of resilient spring contact 54 is positioned beneath the lower surface of the cup-shaped portion 57a of the contactor and by virtue of its resilience, yieldably engages said contactor forming a continuous electric contact therewith in angular positions of the contactor.

The upper surface of web 33 is provided with a pair of integral raised portions 60 on opposite sides of the recess 36, having concave upper surfaces forming projections adapted to serve as insulating detents for yieldably holding the wings 57b of contactor 57 positioned transversely of the casing 20. One of these raised detents is split, as shown by the slot 56 through which the tip 55 of spring contact 54 extends.

The resistor element of the control device is in the form of a resistance coil 85 which comprises resistance wire wound around an insulating core 86, the element being press-fitted in the slot 45 of the casing half 20a.

In accordance with the invention only the sides of the slot 45 are made to engage and closely fit the resistor element of the control device, the bottom of the slot being spaced an appreciable distance from the element as shown in Figs. 3 and 4, except at the slot ends where the bottom is raised to engage the ends of the insulating core 86. By this construction an air space is provided between the outside wall of the casing half 20a and the resistance coil 85 of the resistor element, and I have found that a relatively small air space of $1/16$ " or so is sufficient to effectively reduce heat exchange between the outer wall of the casing half and the resistor element, eliminating heat by conduction and greatly reducing heat by radiation. As a consequence, during the normal operation of the control device the heat which is present in the resistance coil 85 does not produce a distinctly noticeable hot spot in the exterior wall of the casing half 20a as was heretofore the case. By this construction, therefore, there is obviated the need for any shields or other insulating plates on the exterior of the casing half 20a to prevent a user from noticing the heat of the control device.

The terminals 46 and 48 carry a pair of metal conductive clips or retainers 87 and 88 which extend toward the recess 36 and have narrowed contact surfaces as shown in Fig. 2 for engagement

with the wings 57b of the contactor 57. The clips 87 and 88 overlie and are clamped against the opposite ends of the resistance coil 85. The narrowed contact surfaces of the clips 87 and 88 are preferably flat so that they do not act as detents when engaging the wings 57b of the contactor 57.

A flat metal segment or sector contact 89 is provided to extend arcuately around the side of the recess 36 opposite the slot 45, the said contactor being anchored by a terminal screw 67 and overlying the arcuate portion of the web 33 and terminating adjacent the raised insulating detents 60 of said web.

According to the present invention only one of the clips 87 and 88, namely the latter, is made to form electrical contact with the resistance coil 85. The metal clip 87, however, is insulated from the resistance coil 85 by the provision of a thin insulating strip 87a, which may be of fiber or the like, and which is interposed between the clip and the resistance coil.

The structure of the control device is such that it is intended, when shifting the adjustment disk 25 from "off" to the starting low position, that the wings 57b of the contactor 57 simultaneously engage, on the one hand the contact segment 89, and on the other hand the retainer finger or clip 87. Heretofore this clip 87 was not insulated from the resistance coil 85, but formed an electrical connection thereto. Due to variations in the dimensions and tolerances of the various component parts of the control device, I have found that the one web 57b of the contactor 57 may be caused to engage the retainer clip 87 without the opposite web 57b engaging the contact segment 89, and in the past this has resulted in an undesirable condition in that all of the current through the control device was made to pass through the resistance coil 85, producing excessive heating of the latter and resulting in an undesirable condition. However, by the interposition of the insulating strip 87a so as to insulate the clip 87 from the resistance coil 85, this situation is prevented from occurring, since by the time that one web 52b has engaged the first convolutions of the resistance coil 85 adjacent the clip 87, the other web 57b will surely be in engagement with the contact segment 89. Of course, during the time that the clip 87 is being engaged by the one web 57b no current can flow through the resistance coil 85 due to the insulation between the clip and coil 85, and there is thus obviated a condition which was potentially dangerous.

The dial 27a has words designating the position of the switch and also graduated scales extending over arcs which correspond with the energizing adjustment ranges, said scales having numerical indicia which increase from low to high. All of the indicia on the dial 27a are consecutively visible in the sight opening 26, as shown in Fig. 1, when the wheel 25 is turned.

To complete the connections of the control device, terminal screw 67 is connected by a conductor or bus bar 70 to terminal screw 59, and hence to conductor 52a.

As a result of the above construction, contactor 57, when rotated by disk 25 out of its transverse, insulated detent-engaging position in the casing 20, forms a bridge between sector contact 89 and various points on the resistance coil 85, or its terminal clips 87 and 88, and is accordingly adapted to connect these elements with terminal 31 through the spring contact 54-55.

The wiring diagram of the control device of Figs. 1 through 8 and a heating pad to be con-

trolled thereby is shown in Fig. 9. The heating pad here comprises a main heating coil 92 with a pair of safety devices 93, such as fuses or thermostats (preferably the latter) included in its circuit. One end of the main heating coil 92 is connected to terminal 51 by conductor 52b, and thence through conductor 53 to input terminal 30 and conductor 28. The opposite end of the coil 92 is connected in series with a normally closed bimetal switch 94. The latter is connected through a pair of parallel circuits to the other input terminal 31 and its associated conductor 28.

One of these circuits traverses conductor 52c to terminal 48 and its associated clip 88 at one end of the resistance coil 85, then through the turns of the latter coil included between clip 88 and contactor 57, and finally through the latter and spring contact 54-55 to input terminal 31.

The other parallel circuit from the bimetal switch 94 to terminal 31 includes an auxiliary heating coil 95 in the heating pad, which is connected by conductor 52a to terminal 50. From the latter, it traverses bus bar 70, sector contact 89 and contactor 57, rejoining the first-described circuit at spring contact 54-55, carried by input terminal 31.

The auxiliary heating coil 95 is adapted, either alone, or in conjunction with the main heating coil 92 to control the temperature, and hence the operation, of the bimetallic switch 94. When the temperature of the bimetallic switch 94 is sufficiently raised by the heat generated in coil 95, possibly supplemented by that generated in coil 92, switch 94 opens, interrupting the circuit through coil 92 as well as the aforesaid parallel circuits. On cooling sufficiently, the bimetallic switch automatically recloses and reestablishes the circuits.

It will be observed that contactor 57 upon clockwise rotation from the position in which it engages insulated detent 60 initially engages clip 87 at one end of the resistor coil 85 and simultaneously, sector contact 89. Referring to the wiring diagram of Fig. 9, it will be seen that no current will flow from the contactor 57 and retainer finger or clip 87 to the resistance coil 85, since the latter and clip are insulated from each other. Instead, current flows from the contactor 57 to the contact segment 89 and thence through the wire 70, terminal 59, wire 52a to the thermostat heater 95. From here current flows through the thermostat 94, heating element 92, safety thermostats 93 and back through the return wires 52b and 53 to the other current supply wire 28.

This connection causes a maximum heating of the thermostat heater 95 and therefore results in a maximum activity of the thermostat, causing an extremely low heat in the heating element 92 of the heating pad, and this extremely low heat I term a "low-low" heat.

Upon continued clockwise movement of the contactor 57 it will, while remaining in engagement with sector contact 89, leave the retainer clip 87 and engage the first few convolutions of the resistance coil 85. For this position, the current which passes through the thermostat heater 95 is also by-passed through the resistance coil 85, resulting in a lesser heat in the thermostat heater 95 and less activity of the thermostat 94. As a consequence the heating element 92 of the heating pad will be maintained at a warmer temperature than the low-low heat mentioned above, and this warmer temperature I term "low", since it is analogous to the usual low heat encountered

in heating pads. Upon continued clockwise movement, contactor 57, while remaining in engagement with sector contact 89, moves across the coil 85 including progressively fewer and fewer turns of the resistance 85 in parallel with the auxiliary heating coil 95. Finally, it reaches clip 88 at the opposite end of said resistance coil. At this point, the resistance 85 no longer remains in the circuit, while auxiliary coil 95 is shunted, and the full line voltage is impressed across the terminals of the heating coil 92.

Variations and modifications may be made within the scope of this invention and portions of the improvements may be used without others.

I claim:

1. A control rheostat for connection into the cord of a heating pad or the like, comprising a hollow casing formed of insulating material and adapted to be held in the hand; and electrical control means in the casing, including a heatable and heat-dissipating resistor separated from the outer wall of the casing overlying the same by an appreciable air space to minimize heat exchange between the resistor and casing wall whereby the latter adjacent the resistor is maintained relatively cool during normal heating of the resistor.

2. A control rheostat for connection into the cord of a heating pad or the like, comprising a hollow casing formed of insulating material and adapted to be held in the hand; and electrical control means in said casing, including an elongate heatable and heat-dissipating resistor secured at its ends to the casing, said resistor intermediate said ends being separated from the outer casing wall overlying the same by an appreciable air space to minimize heat exchange between the resistor and casing wall whereby the latter adjacent the resistor is maintained relatively cool during normal heating of the resistor.

3. A control rheostat for connection to the cord of a heating pad or the like, comprising a hollow casing formed of insulating material and adapted to be held in the hand; and electrical control means including a resistance coil and a heat-insulating core on which said coil is wound, said core being secured to the casing and said coil being separated from the wall of the casing overlying the same by an appreciable air space to minimize heat exchange between the coil and casing wall whereby the latter adjacent the coil is maintained relatively cool during normal heating of the resistor.

4. A control rheostat for connection into the cord of a heating pad or the like, comprising a hollow casing formed of insulating material and adapted to be held in the hand; and electrical control means including an elongate resistance element comprising a resistance coil wound on and between the ends of an elongate heat-insulating core, said core at its ends being secured to the casing and said coil being separated from the wall of the casing overlying the same by an appreciable air space to minimize heat exchange between the coil and casing wall whereby the latter adjacent the coil is maintained relatively cool during normal heating of the coil.

5. A control rheostat for connection into the cord of a heating pad or the like, comprising a hollow casing formed of insulating material and adapted to be held in the hand, said casing having at least one generally flat hand-engaging outer surface and a relatively thin wall at said surface; and electrical control means including an elongate heatable and heat-dissipating re-

sistor mounted in the casing with its side adjacent the said thin wall and separated therefrom by an appreciable air space to minimize heat exchange between the resistor and thin wall whereby the said exterior flat surface of the casing is maintained relatively cool during normal heating of the resistor.

6. A rheostat comprising a supporting body; a manually operable member rotatable on the body and having a pair of electrically connected contact arms extending from it in opposite directions; a metal contact segment extending along one side of the rotatable member, said segment being engageable by one of the contact arms; an elongate resistance element extending along the other side of the rotatable member, and engageable by the other contact arm; and means for securing the resistance element to the body, including a metal retainer finger overlying one end of said element, said finger being engageable by said other contact arm substantially simultaneously with engagement between the one arm and said segment, and said finger being insulated from said resistance element.

7. A rheostat comprising a supporting body; a manually operable member rotatable on the body and having a pair of electrically connected contact arms extending from it in opposite directions; a metal contact segment extending along one side of the rotatable member said segment being engageable by one of the contact arms; an elongate resistance element extending along the other side of the rotatable member and engageable by the other contact arm; and a pair of metal retainer fingers for the resistance element, said fingers overlying the ends of the element and being engageable by said other contact arm substantially simultaneously with engagement between the one arm and said segment, and one of said fingers being insulated from said resistance element.

8. A rheostat comprising a supporting body; a manually operable member rotatable on the body and having a pair of electrically connected contact arms extending from it in opposite directions; a metal contact segment extending along one side of the rotatable member and engageable by one of the contact arms; an elongate resistance element extending along the other side of the rotatable member and engageable by the other contact arm; means for securing the resistance element to the body, including a metal retainer finger overlying one end of said element and engageable by said other contact arm substantially simultaneously with engagement between the one arm and said segment; and a thin strip of insulating material interposed between said finger and resistance element to insulate the latter from the finger.

9. A rheostat comprising a body of insulating material; a manually operable member rotatable on the body and having a pair of electrically connected contact arms extending from it in opposite directions and yieldable thereon, said body having pairs of integral, spaced projections on opposite sides of the rotatable member, said projections being traversable by the contact arms and providing detents for said arms; a metal contact segment extending along one side of the rotatable member and between the pairs of projections of the body, said segment being engageable by one of the contact arms; an elongate resistance element extending along the other side of the rotatable member between the pairs of projections of the body, said element being engage-

11

able by the other of the contact arms; and a pair of metal retainer fingers for the resistance element, located respectively adjacent corresponding projections of the said pairs, said retainer fingers overlying the ends of the resistor element and being individually engageable by one of said contact arms substantially simultaneously with engagement between the other arm and said segment, and one of said fingers being insulated from said resistance element.

10. In a heating device, a thermostatic switch; a heater for the thermostatic switch; a supporting body; a manually operable member rotatable on the body and having a pair of contact arms electrically connected together and extending from it in opposite directions; a metal contact segment extending along one side of the rotatable member, said segment being engageable by one or the other of the contact arms and being connected with one point of said heater; a resistor extending along the other side of the rotatable member, said resistor being engageable by one or the other of the contact arms and having one point connected with another point of said heater; means for securing the resistor to the body, including a metal retainer finger overlying one end of said resistor, said finger being engageable by either of said contact arms substantially simultaneously with engagement between the other arm and said segment, and said finger being insulated from said resistor; a pair of current supply wires, one of said wires being connected with said contact arms; and electric heating means connected with the connection between the resistor and heater, and connected with the other current supply wire, the said thermostatic switch being connected for controlling the circuit of said heating means.

11. In a heating device, a thermostatic switch; a heater for the thermostatic switch; a supporting body; a manually operable member movable on the body and having a pair of contact arms electrically connected together and extending from it generally in opposite directions; a metal contact plate extending along one side of the movable member, said plate being engageable by one of the contact arms and being connected with one point of said heater; a resistor extending along the other side of the movable member, said resistor being engageable by the other of the contact arms and having one end connected with another point of said heater; means for securing the resistor to the body including a metal retainer finger overlying the unconnected end of said resistor, said finger being engageable by said other contact arm substantially simultaneously with engagement between the one arm and said plate and said finger being insulated from said resistor; a pair of current supply wires, one of said wires being connected with said contact arms; and electric heating means connected with the connection between the resistor and heater and connected with the other current supply wire, the said thermostatic switch being connected for controlling the circuit of said heating means.

12. A switch contactor assembly comprising a rotatable member having a manually engageable portion, and having extending transversely of its axis a pair of shoulders located on opposite sides of said axis; a switch blade; means guiding the switch blade on the member for axial movement; and stop means preventing removal of the blade from the member in one axial direction, said

12

blade having a pair of oppositely located hooks engaging said shoulder and preventing removal of the blade from the member in the other axial direction.

13. A switch contactor assembly comprising a manually engageable wheel having a pair of openings through it from one side to the other, said openings being on opposite sides of the wheel axis; and a switch blade extending across one side of the wheel and having a pair of hooked arms extending through the openings in the wheel and engaging the other side of the latter for preventing removal of the blade from the wheel.

14. A switch contactor assembly comprising a manually engageable wheel having a pair of openings through it from one side to the other, said openings being on opposite sides of the wheel axis; a switch blade extending across one side of the wheel and having a pair of hooked arms extending through the openings in the wheel and engaging the other side of the latter for preventing removal of the blade from the wheel; and a spring urging the blade away from the one side of the wheel and urging the hooked arms toward engagement with the other side of the wheel.

15. A switch contactor assembly comprising a rotatable plate having a pair of openings through it from one side to the other, said openings being on opposite sides of the plate axis; and a switch blade extending across one side of the plate and having a pair of hooked arms extending through the openings in the plate and engaging the other side of the latter for preventing removal of the blade from the plate.

16. The method of assembling a rotary switch blade member having a pair of oppositely located deformable hooked arms to a rotary actuating member having opposite shoulders adapted for co-operable engagement with said arms, which includes the steps of bringing the said members axially together to locate the arms adjacent the cooperable shoulders, and then forcing the members axially toward each other to apply a deforming pressure on the arms and cause the latter to shift into engageable position with respect to said shoulders, thereby preventing separation of the members.

17. The method of assembling a rotary switch blade member having a pair of oppositely located deformable hooked arms to a rotary actuating member having opposite shoulders adapted for co-operable engagement with said arms, which includes the steps of bringing the said members axially together to locate the arms adjacent the cooperable shoulders, backing up the said members with tools, and applying pressures to the tools to force the members axially together and deform the arms to cause the latter to shift for engagement with said shoulders so as to prevent separation of the members.
